(57) **CLAIM**

The ornamental design for a dickey, as shown and described.

DESCRIPTION

FIG. 1 is a front elevational view of a dickey showing my design;

FIG. 2 is a right side elevational view thereof, the left side elevational view being a mirror image thereof;

FIG. 3 is a top plan view thereof; and,

FIG. 4 is a rear elevational view thereof.

The broken lines are for illustrative purposes only and form no part of the claimed design. Further, the broken semi-square element of FIG. 1 and the broken semi-rectangular element of FIG. 4 are fasteners that are shown for illustrative purposes only and form no part of the claimed design.
